UNITED STATES PATENT OFFICE

2,536,757

CENTERLESS GRINDING AND POLISHING
MACHINEKenneth W. Macdonald, Arlington, Mass., as
signor to Production Machine Company, Green-
field, Mass., a corporation of Massachusetts

Application November 15, 1949, Serial No. 127,343

4 Claims. (Cl. 51—103)

1

This invention relates to centerless grinding and polishing machines, and the object is to improve and perfect machines of the type shown in prior patent to Rufus W. Fuller No. 1,421,205.

This well known type of "centerless" grinding and polishing machine operates upon cylindrical rods, tubes, pipes or the like, and comprises a grinding or polishing wheel or belt, together with a feeding wheel or belt, which feeding device cooperates with a work support to hold the work being operated upon in proper position and to simultaneously and automatically rotate and feed the same lengthwise during the grinding, polishing, or finishing operation. Such machines necessarily require adjustments to take care of varying diameters of material being operated upon, as well also as adjustments for determining the feeding of the work through the machine for efficient and effective operation.

My present invention is directed to improve such adjustable mechanisms as are necessary and to facilitate the movement of the grinding or polishing wheel or belt to fit the diameter of the work and also to compensate for wear, such adjustment being readily effected during the continuous operation of the machine. Also, the feeding devices, whether a wheel or a belt, require adjustment toward and from the co-operating grinding or polishing instrumentalities to afford the desired pressure on the work, as well as the speed of feeding the work through the machine.

Further important features of the present invention consist in the mounting and arrangement of the feed elements, with means for angular adjustment of the feeding devices to predetermine the speed of travel of the work through the machine, also while in continuous operation, and means to maintain the feeding belt, where a belt is used for the feed, in desired tension during the adjustments, as well as means to permit manual opening of the space between the feeding and polishing devices to apply or remove the work.

I also provide means to automatically and positively position the work support at proper relative position during the adjustment for spacing, the work support being lowered proportionately as the devices are adjusted for work of a larger diameter, and being automatically and proportionately raised when the adjustment is for a smaller diameter of work to be operated upon, eliminating prior loose linkage connections heretofore used.

2

Other important improvements and novelties consist in the construction and arrangement of the machine whereby a motor to actuate the grinding or polishing is mounted in fixed relation on a slide so that both the motor and the entire grinding or polishing and operative connections are movable toward and from the work for spacing and adjusting, as well as to compensate for wear, thus greatly simplifying the connecting and operating means.

Similarly, a separate motor is mounted and arranged on the movable slide carrying the feeding devices as the same are adjusted toward or from the work. This arrangement greatly simplifies the connections and constructions where adjustments necessary are involved, and enables me to also provide a relatively simple and efficient motor for the feed, such as $\frac{1}{2}$ or $\frac{3}{4}$ H. P., and a similarly efficient motor for the grinding and polishing, such as 5 to 7 H. P.

A still further important and novel feature consists in the mounting of feeding instrumentalities which allow for both the adjustments toward and from the work and with a variation in speed, as well as adjusting the angular position of feed, with capacity also for yielding toward and from the work, the feeding devices being held in uniform tension irrespective of the point to which the same are adjusted.

My novel construction for varying the speed of travel of the feeding and work-engaging elements during the continuous operation of the machine and in full view of the operator results in a finer grade of work and maximum efficiency of both the operator and machine.

For this purpose, I mount the feeding devices on a set of parallel links supporting the same in proper alignment with the grinding or polishing elements, and provide a variable speed pulley which is readily adjustable for varying speeds with the driving belt cooperating thereby, while maintaining the belt under proper tension.

My novel arrangement of the parallel link-supporting elements further allows automatically for handling tapered work, permitting the feeding devices to yield during the increasing taper of work as it is fed through the machine without effecting the other adjustments, the swinging action permitted by the parallel links maintaining the feeding devices in proper alignment and position.

Further details, combinations, and novel improvements and advantages will be hereinafter more fully pointed out and claimed.

3

Referring to the drawings illustrating a preferred embodiment:

Fig. 1 is a plan view of my improved centerless grinding machine construction;

Fig. 2 is a side elevational view of the front or operative side of the machine;

Fig. 3 is an enlarged longitudinal cross-sectional view of the line 3—3 of Fig. 1;

Fig. 4 is a cross-sectional view on the line 4—4 of Fig. 3;

Fig. 5 is a cross-sectional view on the line 5—5 of Fig. 3;

Fig. 6 is a cross-sectional view on the line 6—6 of Fig. 7;

Fig. 7 is a cross-sectional view on the line 7—7 of Fig. 2;

Fig. 8 is an end view of the feed belt looking from the left of Fig. 3;

Fig. 9 is a fragmentary view partly in cross-section looking from the left of Fig. 8;

Fig. 10 is a view on the line 10—10 of Fig. 3; and

Fig. 11 is a perspective view on a reduced scale of the supporting frame.

Referring to the drawings, 1 designates generally a rectangular supporting base or frame having legs 2—2 and a top plate 3, which top is provided with slideways 4 and 5 (see Fig. 11). These slideways are arranged substantially opposite each other in the lengthwise portion of the top plate 3, a slide 6 being arranged to traverse the slideway 4, which slide carries the grinding wheel 7 mounted on an upstanding support 8 on said slide 6 and also the motor 9 which rotates the grinding wheel 7. Similarly the feeding devices are mounted on a slide 10 adapted to traverse the slideway 5, which slide carries both the feeding devices and the operating motor therefor, whereby the feeding instrumentalities and their motor and the grinding wheel and its motor are adjustably movable toward and from the work designated at 15, see Figs. 2 and 3, as will be explained.

While I have herein illustrated the grinding wheel 7 and its attached motor, it will be appreciated that the slide 6 may be removed and a duplicate slide fitted therein which would carry a belt-grinding or polishing device and operating motor therefor, the same being interchangeable with the wheel 7 and its motor 9 as herein illustrated.

The wheel 7 is secured at one end of a shaft 11 mounted in suitable bearings 18—18 in the upstanding support 8 and is held in position by discs 19—19 secured by a threaded nut 20 on the reduced end portion 21 of the shaft 11. The opposite end of the shaft carries a pulley 22, preferably a multiple belt pulley as indicated in Fig. 1, with the belts 23—23 driven by a pulley 24 on an armature 25 of the motor 9, which motor is also mounted on the slide 6 by means of a separate sliding support 28, to which the motor 9 is attached by a pair of bands 29—29 and is adjustably secured to the slide 6. In order to tighten the belts 23, a shouldered lug 30 and adjusting screw 31 are provided, which latter is threaded through a block 32 attached to the slide 6. An exhaust chamber 35 is connected to a dust hood 36 extending over the wheel 7 in order to remove the material ground or polished from the work 15 during the operation of the machine, as indicated in Figs. 2 and 3.

In order to afford an adjustment of the slide 6 carrying the wheels 7 and motor 9 toward and from the work 15, I affix to the slide a depending

lug 40 which receives the threaded stem of an adjusting screw 41 (see Fig. 1).

The opposite end of said screw extends through a bracket 42 bolted to the base, said screw 41 having a bevelled gear 44 on a collar 43 keyed or pinned to said shaft 41, and in position to be engaged by a corresponding bevelled gear 45 mounted on a shaft 46 extending transversely of the supporting base or frame and carrying at its opposite end a hand wheel 48 within convenient reach of the operator.

The shaft 46 is mounted to slide lengthwise to mesh or to disconnect the bevelled gears 44 by a slight longitudinal movement. Thus, the slide 6 can be moved into desired adjusted position to accommodate the machine to the varying diameters of the wheel 7 or to compensate for wear on the wheel 7.

The devices for feeding the work in cooperation with the grinding and polishing wheel 7 are carried by a slide 10 in the slideway 5 and comprise an upper and lower frame, connected by parallel links, carrying the power drive and feed-actuating devices all pivotally supported by the slide 10.

Referring to Fig. 2, the motor 12 is carried by supports depending from the upper frame 60 through an opening 50 in the top plate 3, see Fig. 11, said motor being held by a band 51 to which a bracket 52 is secured, said bracket in turn being attached to an upper bracket 53 secured to a pair of vertically extending adjusting supports 54—54, which supports extend vertically through an arcuate slot 11 in the slide 10 and an opening in the plate 3 to the upper frame 60, and are raised and lowered by rotating a wheel 55, having a handle 56 mounted in the upper frame 60, and thereby varying the speed of feed by controlling the effective diameter of the variable speed pulley 73 and travel of the belt 72, to be explained.

This frame 60 is pivotally connected to pairs of links 61—61 and 62—62 on each side of the frame 60 by pivots 63—63 and 64—64, respectively; and at the lower opposite ends said links are pivotally connected to the bottom frame 65, as indicated at 66 and 67, see Fig. 2, all pivots being ball-bearing as indicated at 59, Fig. 5. Guideways 12—12 on the plate 3 hold the slide 10 assembled thereon, and the slide 10 carries the upper and lower frames and connecting elements.

The frame 60 may thus be moved toward and from the work 15 while maintained in horizontal position, said frame 60 carrying the work-feeding devices, the vertical adjusting supports 54, and motor 12.

Mounted in suitable bearings in the frame 60 is a shaft 70 having at one end a pulley 71 connected by a belt 72, with the variable speed pulley 73 mounted on the armature shaft of the motor 12. The belt 72 can be tightened or loosened and the pulley 73 expanded or contracted, to be later explained. On the opposite end of the shaft 70 is a worm gear 74 meshing with a corresponding gear 75 mounted on a shaft 76 carried in suitable bearings in a part 194, to be described, at one end of the frame 60, which shaft has a sprocket wheel 77 connected by a sprocket chain 78 to a shaft 79, having a corresponding sprocket wheel 80 and a pulley 81. Said pulley carries the feeding belt 82 passing over an idler 83, vertically depending, see Fig. 3, said idler 83 being secured on a shaft 84, both shafts 79 and 84 being mounted in suitable bearings on an extension 85 secured to the frame 60.

Thus, power from the motor 12 rotates the belt 82, and the entire work-feeding mechanism can be moved toward or from the work, swinging on horizontal and vertical pivots, and fixed in the positions where so moved and maintained in substantially uniform yielding contact with the work, as will be described.

The adjusting supports to carry the motor 12 and to act on pulley 13 and belt 82 comprise pairs of threaded members, the lower supports 54 being provided with the threaded sockets in which the threaded stems 85 of the connecting members extend, which members pass through tubular bearings 87 formed on the top frame 60, see Fig. 4. One member carries the operating wheel 55 together with a sprocket wheel 88, and the other member has a sprocket wheel 89 connected by a sprocket chain 90. Thus, rotation of the wheel 55 simultaneously raises and lowers the motor 12 to expand or contract the pulley 13.

The lower frame 65 is attached to the slide 10 by a pivot 91 extending through a boss 92 (see Fig. 3) and fitted into a corresponding socket 93 formed on the slide 10. Thus, the entire feeding instrumentalities can be swung horizontally on the pivot 91, thereby adjusting the horizontal line of contact of the feed belt 82 on the work and can be bodily moved toward and from the work 15 on the slide 10. A set screw 94 extends through a curved slot 95' in the frame 65 and is threaded into a tapped recess 96' in the slide 10 (see Figs. 3 and 10), which screw 94 can be tightened to lock the frame 65 in the angular position relative with the slide 10, to which the feeding mechanism may be set for the horizontal angle desired of the feed belt 82 to meet the taper of the work 15, as required.

A rack bar 97 secured to the under part of the slide 10 (see Figs. 3 and 10) is engaged by the teeth of a quarter gear 97, which is keyed in the shaft 46 and turned by the wheel 48 to move the slide 10 and its supported mechanism toward and from the work. The shaft 46 slides lengthwise to engage and disengage the mitre gears 44 and 45 to effect adjustment of the wheel 7 and attached motor and operating connections, as already described. Thus a single hand wheel 48, in convenient position at the operator's side of the machine, is used to adjust both grinding or polishing wheel and the feeding belt toward and from the work.

It is desirable to move the feeding belt 82 away from the wheel 7 without disturbing the adjustments to which the slide 10 and operating devices have been effected in order to place or release the work. For this purpose, I arrange to move the top frame 60 on the parallel links by means of a handle 100 formed with a split base clamped by a threaded screw 101 on a shaft 102 mounted in a bracket 104 on the slide 3 (see Fig. 3) with the opposite end of the shaft keyed to a lever 105 positioned to contact a plug 106 to engage and move the parallel links to the left, viewing Figs. 2 and 3, against the tension of a coiled spring 108. This spring has one end hooked to an extension of the bracket 104 and the other to a bar 110 bolted to the top frame 60, the spring thereby yielding impelling the top frame and feeding belt toward the work.

I prefer to form the extension 112 on the bracket 104 as a cylindrical member, to which the spring 108 may be attached on a part 113 by an adjusting screw 114, and with the cylindrical interior 115 to carry a sliding piston 118, against which the plug 106 will strike when the handle

100 is oscillated to move the upper frame 60 on the parallel links. The outer end of the piston 118 is forked as indicated at 119 (see Figs. 4 and 10) to slide on a vertically depending pin 120 held in a shaft 121 projecting from a holder 122 bolted to the top frame 60.

This construction insures a relatively slow and steady motion to the movement of the top frame as the piston constitutes an air cushion both against the swinging of the handle 100 and the return action of the spring 108.

In order to tighten the feeding belt 82, I mount the shaft 84 carrying the lower pulley 83 on one end of a bell crank arm 125 (see Figs. 3, 6, and 9), the shaft 84 extending through a housing 126 projecting through an opening 127 in the side of the extension 85. The other arm 128 of the bell crank arm is mounted in an extension 130 rearwardly of the part 85, as shown in Fig. 3, and is secured by a headed bolt 131. On the opposite end of the arm 125 is a lug 133 depending from the arm 128, and an expandable spring 135 between the extension frame 85 and the lug 133 exerts a downward tension on the opposite link arm 125, and this added to the weight of the idler 83 gives ample tension on the belt 82. An upwardly extending lug 134 is controlled by thrusting and tightening screws as indicated at 138, Fig. 2. Thus the belt 82 may be loosened for replacement or tightened, and at all times is yieldingly impelled toward the work.

I also prefer to mount the pulleys 80 and 83 on ball-bearing raceways as indicated in Fig. 7 at 137. Preferably, also, the outer peripheries of each belt-carrying pulley 80 and 83 are flanged as indicated at 140.

I find it desirable to supply a positive backing element to support the feeding belt 82 directly opposite to the line of contact with the work 15 between the pulleys 80 and 83. For this purpose, see Fig. 3, I provide a slide 141 in the extension 85 midway between the pulleys 80 and 83, in which slide a headed plunger 144 is fitted with its head 145 holding a metal plate 146 in direct supporting contact with the inner surface of the belt 82, and with a rearward extension formed as a rack bar 148 in mesh with a pinion 149 on a shaft 150. Rotation of the shaft 150 adjusts the pressure of the plate 146 against the belt. Belt guides 151 are carried by the plate 146.

In addition to the horizontal angle obtained by swinging the feeding belt and its operating connections on the pivot 91, which is to fit the machine for operating on tapered work, it is also desirable to adjust the vertical angle of the feed belt on the work to thus also provide, automatically, for the speed of feed or travel of the work past the wheel 7.

For this purpose, the entire extension 85 is supported on the upper frame 60 so as to be capable of being partially rotated about a pivot in alignment with the shaft 70 and with effective operative position of the wheel 7 and belt 82 on the work 15.

I design the upper frame 60 of cylindrical form as shown in Fig. 4 at 180, which encloses a hollow cylindrical casting 181 adapted to turn in bearings 182-182 in the opposite end portions of the frame 60, which casting, in turn, carries ball bearings at 183-183 for the shaft 70 in concentric assembly. A set of gear teeth 185 are formed in the upper quarter of the casting 181 in position to mesh with a worm 186 on a shaft 188 set in bearings in a boss 189 which is a part of the frame 60 and crosswise therein. Thereby, rota-

tion of the shaft 188 rotates the casting 181 and, hence, the vertical angle of the belt on the work.

The locking engagement of worm 186 and teeth 185 serve to hold these parts in adjusted position, but it is desirable to provide a positive lock which will be described. The squared end 189 of the shaft 188 projects to enable a wrench to be applied thereto through an opening 190 in the cover 201, to turn the shaft and effect the adjustment desired. A scale or gauge 191 may be conveniently provided to indicate the relative rotation to which these parts are adjusted. The extension frame 85 may be attached to the supporting casting 181 in any suitable manner. As here shown, I preferably form the end of the casting 181 with a head 194, see Figs. 2 and 3, which enclose the worm 14 on the end of the shaft 78 and the gear 75, the open end of this head 194 having a peripheral flange bolted to the extension 85. To lock these parts in adjusted position, I supply a bolt 195 passing through a slot 196 in a part 195 of the frame 60 and threaded into the head 194 at 198, see Figs. 3 and 5.

To automatically raise and lower a work support 170 as the slide 10 is moved toward or from the wheel 7 to provide space for stock of varying diameter, I fit the lower end of the work support in a holder 171 by threaded connections, see Fig. 3. This holder has a hub 172 frictionally tight on a stud 173 at the upper end of a sliding rod 174 held in an angularly positioned holder 175 affixed to the plate 3. The lower end of the sliding rod 174 has a hub 176 through which a headed bolt 177 extends into a cam slot at 199 formed at a predetermined angle with the holder 175, as part of a bracket 202, secured to the under part of the slide 10, see Fig. 5.

A roll 179 on the bolt 177 is also fitted to traverse the cam slot as the slide 10 is moved and, hence, to pull down or push up the rod 174 and, hence, the work support to adjust the same for varying diameters of work and to hold the work in the proper and efficient line of contact between the wheel 7 and feeding belt 82, as is customary in centerless grinding and polishing machines of this type. A cover 201 is removably fitted to protect the machine against dust, abradings, etc. and the operator also.

While a wheel 7 and belt 82 are herein shown and described, an abrading belt in place of the wheel 7 can be substituted and for this purpose I form the base 1 with a recess 200 to receive the lower idler for such a belt substitution. Also the feed belt 82 can be interchanged with a wheel by removal of the extension frame 85 and replacing with wheel bearing and driving connections.

The operation will now be described. As adjustment of the motor 9 and wheel 7 is only occasionally required, but, if desired, the operator pushes on the wheel 49 until the gears 44 and 45 are in mesh, and then turns the wheel 46 moving the slide 6 in the slideway 4 on the plate 3 as needed. Thereupon the wheel 48 and shaft are retracted until the gears 44 and 45 are in mesh, and the feeding mechanism including the belt 82 and its motor 12 are moved by adjusting the slide 10 in its slideway in the plate 3 to properly space the belt 82 and polishing, grinding, or abrading wheel 7.

The lock nut 94 is loosened and the entire feeding apparatus is swung on the pivot 91 for horizontal adjustment of the feeding belt as required for straight cylindrical or tapered work. During these adjustments the work support 170 is automatically raised or lowered as the feeding

apparatus is moved toward or from the wheel 7, thru the action of the roll 176 traversing the slot 199, secured rigidly to the slide 10 and, hence, insuring a positive and accurate positioning of the work support.

Thereupon, the vertical angle of the belt 82 is adjusted by loosening the locking bolt 195 and turning the shaft 188 to a point indicated on the scale 191 and the locking screw 195 is then tightened. This angular adjustment of the extension 85 and belt 82 provides the desired speed or travel of the work past the wheel 7.

The operator then moves the lever 100, viewing Figs. 2 and 3, swinging the top frame 60 and connections against the tension of the spring 108 to open the working space between the feed belt 82 and wheel 7 and, thereupon, positions the work and releases the lever 100, and the frame 60 is forced slowly back, because of the dashpot effect of the piston 118, thereby yieldingly holding the belt 82 in contact with the work in cooperation with the spring 135 on the idler 83.

Motors 9 and 12 are then energized and the 25 polishing, grinding, and feeding of the work proceeds. If tapered work is being operated upon, the frame 60 moves proportionately on the parallel links supporting it, as the taper of the work increases, while the belt 82 is maintained in vertical position and alignment without any loosening of the driving and belt-tightening actions. The wheel 55 is rotated to control the speed of travel of the feeding belt by expanding or contracting the variable speed pulley 73—such as a Reeves pulley—while keeping the driving belt 12 tight. Covers 201 and 203 aid in protecting the machine and the operator against accidents and also protect the working parts against dust or particles ground off by the wheel 7.

The belt feed can be easily removed from the head 194 and a wheel feed substituted if desired. 40 Similarly, the polishing wheel 7 can be quickly replaced by substituting a belt and its attached mechanism. Thus, the main base and slides, frames, and motors can be standardized and kept in stock to be fitted with belt or wheel-polishing or feeding apparatus, as ordered.

I claim:

1. A centerless grinding and polishing machine of the kind described, comprising a working element, work-feeding elements, a work support, a slide adjustably movable toward and from the working element, a frame pivotally attached to said slide, a second frame supported on the first-mentioned frame by parallel links, said second frame carrying the work-engaging feeding elements, and connections between the second frame and work-engaging elements providing for angular adjustment relatively with the work.

2. In a centerless grinding and polishing machine of the kind described, a slide carrying the working elements and an operating motor therefor, a second slide carrying work-feeding elements and an operating motor connected therewith, independently adjustable means to move the working element and motor and the work-feeding elements and its motor toward and from each other, in combination with means including parallel links and means tensioning the feeding element toward the work, together with individually adjustable devices to predetermine the horizontal and vertical angle of the feeding elements on the work.

3. In a centerless grinding and polishing machine of the kind described, a working element, work support adjacent said element, work-

feeding instrumentalities adapted to hold and feed the work on said support and in contact with the working element, comprising a slide adjustable toward and from the work, a frame pivotally attached to said slide and angularly adjustable thereon, a second frame supported by parallel links on the first frame, yielding means to move the second frame toward the work, said second frame carrying a work-engaging and feeding belt adjustable about a horizontal angle, said belt including a driving pulley and an idler, the idler being mounted on a bell crank lever, and independently adjustable and yielding tensioning means acting on the idler to hold the belt tensioned against the work.

4. A centerless grinding and polishing machine of the kind described, comprising a working element, a work-feeding element, a movable work support between said two elements, a motor to drive said feeding element, a slide carrying said feeding element and motor, means to adjust the slide toward and from the working element, a bracket rigidly secured to said slide, a slot in said bracket angularly positioned relatively with

the direction of travel of the slide, in combination with connections from said angular slot to the work support to move said work support in co-operative relation with the travel of the work-feeding slide.
